CASKET HANDLING APPARATUS

Arthur O. Spriggs and Darrell E. Briner, Springfield, Ohio, assignors to The Champion Company, Springfield, Ohio, a corporation of Ohio

Application August 22, 1944, Serial No. 550,622

16 Claims. (Cl. 27—26)

1.

This invention relates to casket placers.

It is the principal object of the invention to provide a casket placer which is relatively light in weight, simple and economical in construction and capable of being readily assembled and disassembled and adjusted to a desired size, and which receives the casket and moves the same forward to the proper lowering position where the casket is then transferred smoothly and quietly to the lowering device.

It is a further object to provide such a device which automatically transfers the casket to the lowering device at the proper position thereon and then quietly removes itself from beneath the casket so that it is out of the path of the same as it is lowered while remaining in fully accessible position for subsequent removal.

It is a further object to provide a casket placer having fluid actuated brake means for assuring smooth and quiet operation in the handling and movement of the casket.

It is a further object to provide a casket handling apparatus incorporating closure means for the grave opening which normally maintain the opening closed but provide for the opening thereof as the casket is lowered.

Other objects and advantages will be apparent from the following description, the accompanying drawing and the appended claims.

In the drawing,

Fig. 1 is a broken plan view showing a casket placer constructed in accordance with the present invention in position upon a lowering device;

Fig. 2 is a side elevation of the same;

Fig. 3 is a vertical sectional view on an enlarged scale through the end fitting and the telescoping track member on the line 3—3 of Fig. 1;

Fig. 4 is a vertical sectional view on the same scale as Fig. 3 through the end frame member showing the telescoping relation and the roller for receiving the casket on line 4—4 of Fig. 1;

Fig. 5 is a plan view of one of the hydraulic brake elements with the cover removed;

Fig. 6 is a vertical sectional view on the line 6—6 of Fig. 5;

Fig. 7 is a vertical sectional view on the line 7—7 of Fig. 5;

Fig. 8 is a vertical sectional view on the line 8—8 of Fig. 5;

Fig. 9 is a broken end elevational view showing the carriage in its normal or operative position upon the track;

Fig. 10 is a plan view similar to Fig. 9, with certain parts being broken away;

2.

Fig. 11 is a side elevational view of the carriage in position upon the track;

Fig. 12 is a detail view of the hinge bracket used with the carriage;

5 Fig. 13 is a perspective view of the carriage in its normal or casket supporting position with the casket being indicated in dash lines thereon;

Fig. 14 is a view in perspective of the carriage in its release position;

10 Fig. 15 is a view through the hinge means for supporting the closure and on the line 15—15 of Fig. 1;

Fig. 16 is a sectional view through the means for supporting the closure by means of the tapes, and on the line 16—16 of Fig. 1;

15 Fig. 17 is a somewhat schematic view showing the relationship of the several parts at the time when the carriage begins its movement from its normal to its release position, to transfer the casket from the carriage to the tapes; and

20 Fig. 18 is a detailed view showing the spring detent as used on the hydraulic brake at the receiving end of the device.

In the handling of caskets, it is common practice to provide a lowering device on which the casket may be placed for lowering into the grave. However it is usually found undesirable, and may even prove dangerous to require that the casket be manually carried along the sides of the grave, in order to position it in proper location upon the lowering device. For this reason it is desired to make use of a casket placer which receives the casket at one end of the grave and which then transports the casket forwardly into its proper position over the lowering device without requiring manual lifting of the advancing end of the casket.

25 It is highly important that the casket placer be portable and capable of ready assembly and disassembly, and that it be adjustable as to size as required for different size graves and to accommodate different size caskets. It is desirable that the device itself function smoothly and quietly throughout so that it does not give the appearance or sound of a piece of mechanism while it is in the course of operation. It is also desirable that the casket placer be of such construction that it is readily withdrawn or removed from beneath the casket when the latter is in proper position above the lowering device, thereby providing for transferring the casket from the placer onto the lowering device. This operation should also be accomplished smoothly and quietly, and preferably without requiring manual lifting or other attention.

In accordance with the present invention these desirable characteristics are accomplished in a highly satisfactory way. The device is portable in a disassembled and compact form and may be readily assembled to any desired size, and providing for receiving the casket thereon without shock or noise. With the one end of the casket in position upon the placer, and the casket being manually supported at its other end, it is moved forward over the grave without requiring any manual support at the sides of the grave. When the casket reaches a predetermined position at which it is desired to transfer the same to the lowering device, such operation takes place automatically, so that assurance is provided that in all cases the casket will be positioned accurately and in the desired position, without the necessity of manual attention.

Further, this transferring operation takes place smoothly and quietly, the casket placer automatically withdrawing its support and removing itself not only from supporting relation with the casket, but to a clearance position so that it will be out of the path of the casket as it is lowered. In addition, the casket placer itself remains in its original position on top of the lowering device, such that it is easily accessible, and can be readily removed after the casket is lowered.

In addition, in accordance with the present invention, closure means may be provided if desired for closing the grave opening, so that as the casket is moved into place and before it is lowered, the entire grave opening is substantially closed. The closure means is related in its movement to the tapes which are incorporated as part of the lowering device, and through such relationship the closure means is moved to open position gradually as the casket is lowered, so that an effective closure of the grave opening is maintained at all times.

Referring to the drawings which disclose a preferred embodiment of the invention, the lowering device is indicated generally in Figs. 1 and 2 of the drawing, comprising corner posts 10 which are connected by longitudinally extending tubular side members 12. The tubular members are suitably fitted to the corner posts, and have parts which are rotatable in the usual manner for receiving a rolled up pair of tapes 14 and 15 in suitably spaced locations thereon. The frame is completed by tubular end members 16, all such tubular frame members being made of telescoping construction to provide for the adjustment of the size of the lowering device as to both length and width.

The casket placer is shown as composed of a frame separable from and applicable to the assembled lowering device. It comprises a pair of corner fitting members 20 and 21 at the receiving end, and another pair of such members 22 and 23 at the release end. Such members have corner portions 24 which fit upon and against the corner posts 10 of the lowering device in order to guide and support the casket placer in position thereon. In addition the several corner fittings are provided with downwardly open cylindrical-shaped brackets 27 which are adapted to be received over the tubular part of the lowering device, to provide for proper support of the frame thereon.

The longitudinally extending parts of the corner fittings 20 and 21 have a substantially T-shaped slot formed therein as indicated at 30 in Fig. 3. These slots provide for adjustably receiving therein a pair of longitudinally extend-

ing track members 32 and 33 which carry brackets 34 at spaced points similar in construction and function to brackets 27. Corner fittings 22 and 23 have similarly arranged slots, although these slots are substantially L-shaped inasmuch as that corresponds with the cross section of the track members adjacent these fittings at the release end.

Fittings 20 and 21 also have a slot 35 formed in their transversely extending parts, as shown in Fig. 4 of the drawing, providing for adjustably receiving therein an end frame member 37 which may be made of angular material substantially L-shaped in cross section. Similarly fittings 22 and 23 are provided with an L-shaped slot for adjustably receiving the end frame member 38 at the release end of the device. Preferably all of such members are made of relatively light weight material in order to make them readily portable, and adjustable. From the above description it will be understood that the frame so provided is adapted to be positioned in supporting relation upon and substantially directly over the lowering device itself, and provides for ready adjustment as to both length and width through the telescoping relation of the several parts as described. Since the track and the entire frame structure of the placer is located above and supported throughout upon the lowering device, an adequate and firm support is thus provided.

The longitudinal track members 32 and 33 are each formed with an outer flange 40 which is continuous over the length of the track, and with a central vertically extending web 42 which is also preferably continuous. Inwardly, the tracks are formed with an inner flange 44 which is level with flange 40 over the major portion of the length of the track, but which is formed with a downwardly curved section 45, at a definite point along the length of the track and toward the release end. The remainder of the inner flange 44 is relieved, although the outer flange 40 continues up to the release end.

At the receiving end of the device, which is represented at the right-hand end of the device as shown in Figs. 1 and 2, the end fittings 20 and 21 on the parts thereof which project toward each other are formed with forwardly extending arms 50 and 51 which are drilled to provide a support for rollers 52, 53, such rollers being supported with their upper surfaces standing slightly above the level of the fitting itself. Such rollers thus form supports for the casket, indicated in dotted lines at 55, as it is moved into position at the receiving end of the device to prevent the same from riding on the fixed parts of the frame.

Means are likewise preferably provided for avoiding any shock or noise as the casket is placed in position, such means comprising a fluid actuated brake element. As shown, this element includes a central tongue 60 having a base portion 61 which normally projects substantially horizontally and is preferably provided at its free end with a spring member 62 which normally engages over a part of the movable carriage to be herein-after described, in order to prevent premature movement of the carriage away from the casket receiving position. The brake element serves to receive the rear end of the casket after it has left the supporting rollers and thereupon gradually lowers and releases the casket into its proper position on the tapes of the lowering device, while avoiding any undesired shock condition.

The hydraulic unit is preferably made in two duplicate parts, which are located in the housings 64 at either side of the base 61 of the tongue, the housings being suitably fastened in position upon the end frame member 37 as by bolting thereto. The base 61 is provided with oppositely extending shafts 65 which project into the respective housings and about which the tongue pivots for the purpose of developing the desired braking action.

One of such units is illustrated in Figs. 5 through 8, and will now be described. The working shaft 65 extends through a bearing bushing 67 mounted in the wall of the housing 64, into a fluid chamber 68 which is formed therein. A packing gland 69 prevents escape of fluid along the shaft, and the fluid chamber is closed by a cover plate 70.

Within the chamber, a crank arm 72 is fastened to the end of shaft 65, the crank engaging a connecting rod 73 which fits over a pin 74 secured in piston 75. The piston is ported as shown at 76, and a ball check 77 is provided in the passage to permit upward movement of the piston substantially without braking action. This upward movement corresponds to an upward lifting movement of the tongue 60, providing for the lifting of the tongue to its operative position substantially without load. However the ball check seats upon an opposite movement of the piston, thereby subjecting the fluid beneath the piston to compression.

A by-pass passage 80, the bottom end of which is closed by a rivet 81 is provided to establish communication from the space below the piston to the fluid chamber thereabove, and the size of such passage is regulated by a throttling valve 82 having an adjusting head 83 which is accessible upon the outside of housing 64. It will thus be clear that upon the adjustment of screw 83, the desired degree of resistance to the downward movement of the casket may be regulated and predetermined, to permit the lowering of the tongue and of the casket at the desired rate.

The carriage itself is mounted for longitudinal travel upon the track members above described. The carriage comprises at each side a housing 90 which is provided with spaced interior depending flanges 91. Shafts are mounted adjacent opposite ends of the housings and provide for mounting the rollers 93 so that there are rollers adjacent both the forward and the rearward ends of the carriage. As shown in Figs. 9 and 10, these rollers 93 are mounted in such position that they engage the track portion 40 outwardly of the central flange 42 so that they provide for continuous support of the housings and hence of the main frame of the carriage throughout the entire travel thereof. Vertical guide rollers or bumpers 95 are fixed in the carriage adjacent the forward and rearward portions thereof, and are adapted to engage on the inner vertical faces of the webs 42 to thereby provide lateral stability for the carriage during its travel.

On the inner side of each carriage, and preferably formed integrally with the housings 90, there are provided socket members 100 which are apertured to receive therein the upper tubes 102 and lower tubes 103, such tubes being secured in place therein by means of pins 104. As shown, the two tubes are preferably not directly above each other, the upper tube 102 being located forwardly somewhat with respect to tube 104 to more readily receive the casket in position thereon.

The tubes are slidably received over internal rods indicated at 106 and 107, respectively, to thereby provide for adjustment in the spacing of the two sides of the carriage, throughout telescoping action of the interfitting tubes and rods.

A pair of hinge members 110 are also mounted on the upper and lower sets of tubes, being suitably spaced from each other substantially as shown. Such hinge members have depending arm 110 portions 112 within which there is rotatably received a cooperating hinge arm 113, such arm having a broad and flat face 115 extending forwardly therefrom, and providing a seat upon which the casket may rest.

The hinge arms 113 at their forward end are received over the tubes 120, which are also adjustable relative to each other through the provision of an inner telescoping rod 121. The hinge arms 115 are suitably secured to the respective tubes 120.

Tubes 120 extend respectively toward the opposite housings 90, and adjacent their ends are provided with sockets 124 to which there is fixed a bracket 125 that is adapted to support a roller 126.

As will be clear from the drawing the inner side wall of the housings 90 is notched out as shown at 127 to provide a recess for the reception of brackets 125, the roller 126 thus being adapted to travel along the inner flange 44 of the track.

In this position it will also be clear from the drawing that rollers 126 are supported at the same level as rollers 93, so that the forwardly projecting part of the pliers, comprising the tubes 120 and the bracket arms 115, stands in normal or casket receiving position which is substantially horizontal. These parts are however not in fixed relation with respect to the housings 90, and it will thus be apparent that upon the forward travel of the carriage to the position where the inner flanges of the track are relieved, as shown at 45, rollers 126 will ride down such inclined surfaces, and thus provide for the lowering of this portion of the carriage below its horizontal position. Further when the rollers ride off the end of the track portions 45, the forward portion of the carriage will be allowed to move downwardly, through the action of the hinge means 112 to a position where such portion is substantially vertical, and hence out of the path of lowering movement of the casket. However the carriage itself including the rollers 93 and the housings 90 occupy the same level and thus do not permit any part of the carriage to fall into the grave; the entire carriage thus remains fully accessible, so that it can be readily removed at the level at which it is operated, when desired.

It is also desired to brake and check the action of transferring the leading end of the casket from the carriage to the lowering device, and to avoid any objectionable shock or noise in the course of such operation. For this purpose a second tongue 130 is positioned in the cross frame member 38 at the release end of the machine, hydraulic brake or check elements 131 and 132 being provided, the construction of which is essentially the same as that of the units previously described and associated with tongue 60. The tongue 130 however is preferably formed with an offset so that instead of normally resting on top of the cross bar 120, it is positioned with its upper surface level with the lower side of the bar as shown in Fig. 17.

Fig. 17 shows the relative position of the several parts at the time when the transferring action takes place. Thus as shown, the carriage

75

with the casket in position thereon is moving toward the release end or to the left as illustrated in that view, the rollers 93 being supported on the outer flange track 40, and roller 126 being supported upon the inner flange track 44. The base of the casket is supported on the top of tube 120 by webs 115 and hence is at the level indicated by the line 132. The tongue 130 is shown, and it will be seen that the upper surface of the tongue in its normal position prior to the movement of the carriage thereover is at about the level of the top of the inner track flange 44.

In operation, the carriage is normally prevented from moving away from its casket receiving position by the light engagement of spring detent 62 with the cross bar 129 of the carriage. With the forward end of the casket resting on the carriage, and as the latter is moved forward on its track, the cross bar 129 pulls out from beneath the spring detent, allowing the carriage to travel freely across the grave opening, the rear end of the casket being supported on rollers 52, 53.

As the carriage moves to the left the two opposite wheels 126 travel downwardly over the curved track portion 45, thereby gradually lowering the tubular member 126, the lower side of which thereupon engages the top portion of tongue 130. This effectively checks any sudden dropping movement of the pivoted part of the carriage, and assures that the forward end of the casket will be lowered gradually until it has been transferred to the tape 14. As this occurs, the forward movement of the casket is stopped, the casket thus being positioned quite accurately and without requiring any unnecessary elongation of the grave beyond a very limited clearance at either end, the casket in its final position on the tapes having just sufficient clearance to pass between the respective housings 64 and 132.

Meanwhile, the pivoted part of the carriage, under the action of gravity, bears against tongue 130, to apply a gradual load to the hydraulic unit, which slowly and quietly permits such carriage part to move from the position illustrated in Fig. 13 to that illustrated in Fig. 14. At this time the carriage occupies a position immediately adjacent the release end of the placer frame, with the pivoted part hanging substantially vertically, and hence out of the path of downward movement of the casket. Similarly the rear end of the casket has at this time passed off of rollers 52, 53, and is thus supported on tongue 69 which moves gradually downward to thus lower that end of the casket also smoothly and quietly upon tape 15.

It may also be desirable to provide a closure means for closing the grave opening prior to the time when the casket is lowered. This is conveniently accomplished in the device of the present invention through the provision of closure means which may be supported by the track members 32. For this purpose, a pair of doors 140 and 141 are provided which are of suitable width to extend from each side of the frame approximately to the center thereof, leaving some clearance to provide for adjustment in width, and also to permit the downward movement of the tongue 130 therebetween.

Each door is supported by a pair of spaced hinge members 143 including a plate 144 fastened to the lower side of the track members in any suitable manner, and a cooperating hinge member 145 riveted or otherwise suitably secured to

the lower side of the closure itself. The two members are detachably secured together by means of withdrawable hinge pin 146 so that the doors can be assembled in position following the proper assembly of the track and frame members, by the simple insertion of the hinge pins in the proper position. From the arrangement as shown in Fig. 15, it will be understood that the hinges provide for the support of the closure at a level slightly below that of the track members, leaving a space through which the tapes 14 and 15 can extend, the tapes thus being located on the upper side of the two closure members.

In order to provide for the support of the closure members in their horizontal closing position, a bracket 150 of substantially Z shape is provided, one arm thereof being fixed to the door 140 which is notched out as shown at 151 to receive the bracket. The other arm of the bracket extends above the level of the door and has an open end 152, under which the tapes 14 and 15 can be passed into engaging relation. From this arrangement, as shown in Figs. 15 and 16, it will be clear that upon the tightening of the tapes 25 of the lowering device, the tapes will cause the lifting of the brackets 150, to in turn cause the raising of the two closure members, thereby providing for the retention of such members in substantially horizontal relation prior to the movement of the casket into place. During the time that the casket is moved across the grave and into position on the lowering device, the grave opening remains substantially closed. However as the casket is finally lowered into the grave, its base engages the upper surface of the tapes, and through them effects the depression of the doors which open downwardly, to receive the casket, while remaining hingedly connected to the sides of the tracks.

Following the lowering of the casket, it is a relatively simple matter to withdraw the hinge pins 146, whereupon the doors can be withdrawn, preparatory to the disassembly and removal of the entire mechanism. It will also be clear that the presence of the doors does not interfere with the normal practice of slipping the tapes out from beneath the ends of the fully lowered casket, the brackets 150 having their open sides extending outwardly away from each other to facilitate such removal of the tapes. If desired the entire track assembly including the doors may be removed as a unit without the preliminary separation of the doors.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A casket placer of the character described comprising track members, a carriage movable upon said track members, said carriage having a frame and an additional part movable relative thereto from a casket supporting position to a release position allowing the lowering of the casket, and means operable when said carriage reaches a predetermined position upon said track members for causing movement of said additional carriage part to said release position to release the casket thereon for lowering.

2. A casket placer of the character described comprising track members, a carriage traveling upon said track members, said carriage having a

frame and an additional part movable relative to said frame from a normal casket supporting position to a release position allowing the lowering of the casket, means for maintaining said additional carriage part in its said normal position over a portion of the travel of said carriage upon said track members, and means providing for the movement of said carriage parts to said release position at another portion of the travel of said carriage.

3. A casket placer of the character described comprising track members, a carriage traveling upon said track members, said carriage being movable relative to said track members from a normal casket supporting position to a release position allowing the lowering of said casket, means for maintaining said carriage in its said normal position over a portion of its travel upon said track members, means providing for the movement of said carriage to its said release position at another portion of its travel, and means for controlling the movement of said carriage to its said release position to cause such movement to take place smoothly and quietly.

4. A casket placer adapted to be used in conjunction with a lowering device comprising track members supported upon said lowering device, a carriage traveling upon said track members, a portion of said carriage extending in a generally horizontal direction and adapted to receive one end of a casket thereon, means for maintaining said portion in said substantially horizontally extending position over the major part of the travel of the carriage, and means operable at a predetermined point in the travel of said carriage providing for the movement of said portion to a substantially vertical position to release the same from said casket.

5. A casket placer adapted to be used in conjunction with a lowering device comprising track members supported above said lowering device, a carriage traveling on said track members, said carriage having a frame and an additional part adjustably related thereto, means operable over a part of the travel of said carriage, for maintaining said adjustable part in a normal position forming a casket support, and means providing for the movement of said adjustable part to a release position to release said casket onto the lowering device in another part of the travel of said carriage.

6. A casket placer adapted to be used in conjunction with a lowering device comprising track members supported above said lowering device, a carriage traveling on said track members, said carriage having a frame and an additional part pivotally related thereto, means operable over a part of the travel of said carriage, for maintaining said pivotal part in a normal position forming a casket support, and means operable at a predetermined point in the path of travel of said carriage providing for the movement of said pivotal part to a release position to release said casket onto the lowering device.

7. A casket placer adapted to be used in conjunction with a lowering device comprising track members supported above said lowering device, a carriage traveling on said track members, said carriage having a frame and an additional part adjustably related thereto, means for maintaining the support of said frame throughout the travel of said carriage over said track members, and means providing for the support of said adjustable part over only a part of said path of travel to provide for release thereof at a prede-

termined point in said path of travel to effect the transfer of said casket to said lowering device.

8. A casket placer adapted to be used in conjunction with a lowering device comprising track members supported above said lowering device, a carriage traveling on said track members, said carriage having a frame and a part movable relative thereto, outer supporting means engaging said track members for supporting said frame throughout the movement of said carriage, inner supporting means separately engaging said track members inwardly of said outer supporting means for supporting said movable frame part in a normal casket receiving position, a portion of said track members in line with said inner supporting means being removed to allow said inner supporting means to leave the track with accompanying movement of said movable frame part to a position where said casket is released and transferred to said lowering device.

9. A casket placer adapted to be used in conjunction with a lowering device comprising track members supported above said lowering device, said track members including inner and outer tracks, a carriage including a frame and a part movable relative thereto and adapted in normal position to receive a casket thereon, supporting means engaging said outer track for continuously supporting said frame throughout the movement thereof, additional supporting means engaging said inner track for supporting said movable carriage part in said normal position, said inner tracks means being relieved at a predetermined point to allow movement of said movable carriage part to a position where said casket is released while said frame remains supported on said outer track portion.

10. A casket placer adapted to be used in conjunction with a lowering device comprising track means, a carriage mounted on said track means for travel thereover, said carriage being movable from a normal casket supporting position to a release position out of the path of lowering movement of said casket, means for retaining said carriage in said normal position over the major part of its travel on said track means and providing for movement thereof to said release position at a predetermined point in said travel, and fluid actuated means for checking the movement of said carriage to its said release position and causing such movement to take place gradually and quietly.

11. A casket placer adapted to be received over a lowering device comprising end fittings, track members extending longitudinally along said lowering device, means for supporting said track members at spaced points from said lowering device, end frame members, said end frame members and said track members having telescoping relation with said end fittings providing for adjustment of size, a carriage having telescoping portions adjustable as to width to correspond with the spacing of said track members, means for supporting said carriage for travel upon said track members, and fluid actuated means supported upon one of said end frame members for controlling the placing of a casket upon said carriage to provide for the gradual and quiet positioning thereof, said one end frame member having telescoping relation with both of its supporting end fittings providing for maintaining said fluid actuated means in predetermined desired position throughout said size adjustments.

12. In casket handling apparatus, a lowering device having tapes extending transversely there-

of for receiving and lowering a casket, a closure member, hinge means at one side of said closure member for pivotally supporting the same for movement from an upper closing position beneath said casket to a lowered position providing for the passage of the casket therethrough, and a bracket including a pair of arms for retaining said closure member in said upper position, one of said bracket arms being secured to said closure member, the other said bracket arm extending in spaced parallel relation with said closure member substantially transversely of said tapes, said last named bracket arm having an open end adapted for engagement with one of said tapes to support said closure member from said tape providing for the opening of said closure member upon the lowering of said casket on said tapes and providing also for ready disengagement from said tape by transverse movement of said tape after completion of the lowering of said casket.

13. Casket handling apparatus of the character described for use with a lowering device comprising a frame forming longitudinally extending tracks, a casket receiving carriage mounted for free traveling movement upon said frame from a casket receiving position to a casket release position, and means supported adjacent one end of said frame and yieldably engaging said carriage for normally retaining said carriage in its said casket receiving position and adapted to yield under pressure to provide for movement of said carriage and said casket toward said release position.

14. A casket placer adapted to be received over a lowering device comprising corner fittings supported upon said lowering device and each including parts extending longitudinally and laterally at substantially a right angle to each other, unitary track members extending longitudinally along opposite sides of said device adapted to receive a movable carriage thereon, said track members being supported at each end by said longitudinally extending parts of said corner fittings and each of said track members having 45 a telescoping relation at one end with said longitudinally extending part of the adjacent said corner fitting for adjustment as to size providing a continuous track surface between said corner fittings for supporting said carriage in all positions of adjustment, and end members having a telescoping relation with said laterally ex-

tending parts of said corner fittings for adjustment of said casket placer as to lateral size.

15. In casket handling apparatus, a lowering device having tapes for receiving and lowering a casket, supporting means extending longitudinally along the sides of said lowering device, a pair of closure members, hinge means at a side of each said closure member for pivotally supporting the same upon said supporting means for movement from an upper closing position beneath said casket to a lowered position providing for the passage of the casket therethrough, said hinge means including withdrawable hinge pins providing for easy assembly and removal of said closure members, and means spaced from said hinge means for connecting said closure members with said tapes to support said closure members in said closing position until the downward movement of said casket.

20 16. A casket placer adapted to be received over a lowering device and comprising a frame including longitudinally extending track members, a carriage movably mounted on said track members, releasable means on said carriage for receiving and supporting a casket while being moved to a release position on said frame, and fluid actuated means supported at one end of said frame and extending beneath said casket in said release position of said carriage for controlling the transfer of said casket from said carriage to said lowering device to provide for the gradual and quiet positioning thereof in a predetermined position on said lowering device.
